(57) **CLAIM**

The ornamental design for a multipurpose flat chassis vehicle platform, as shown and described.

DESCRIPTION

FIG. 1.1 is a top, front, and left side perspective view of a multipurpose flat chassis vehicle platform embodying the new design;

FIG. 1.2 is a front elevation view thereof;

FIG. 1.3 is a rear elevation view thereof;

FIG. 1.4 is a right side elevation view thereof, to which the left side elevation view is a mirror image thereof;

FIG. 1.5 is a top plan view thereof; and

FIG. 1.6 is a bottom plan view thereof.

The broken lines in the drawings illustrate portions of the multipurpose flat chassis vehicle platform that form no part of the claimed design.

1 Claim, 6 Drawing Sheets
